United States Patent Office

Des. 205,294
Patented July 19, 1966

205,294

GAMEBOARD

Humbert Robertson, 965 Tinton Ave., Bronx, N.Y.

Filed June 7, 1965, Ser. No. 85,599

Term of patent 14 years

(Cl. D34—5)

Fig. 1

The dominant features of my design reside in the portions shown in full lines.

I claim:

The ornamental design for a gameboard, as shown and described.
